United States Patent Office.

J. S. VAN BUREN, OF GREEN ISLAND, NEW YORK.

Letters Patent No. 96,289, dated October 26, 1869.

SUMMER-FURNACE.

The Schedule referred to in these Letters Patent and making part of the same

To all whom it may concern:

Be it known that I, J. S. VAN BUREN, of Green Island, in the county of Albany, and State of New York, have invented a new and valuable Improvement in Summer-Furnaces; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of my invention in central vertical section.

Figure 2 is a horizontal section of same, taken below the grate.

My invention relates to summer-furnaces, and consists mainly in the construction and novel arrangement of devices, whereby such a furnace can be readily adjusted to the top of an ordinary cooking-stove, or, if so desired, used independently.

The letter A, of the drawings, designates outer cylinder of the furnace, which is of sheet-iron.

The letter B, an inner cylinder, of smaller size, connected to the cast-iron bottom C of the furnace, but having its upper edge free, and some two inches below the upper plate D of the furnace.

The smaller cylinder B is tangential to the cylinder A, being attached to it in front.

Within the cylinder B is placed a circular grate, b, supported by three ears, b' b'', riveted to the side of the cylinder.

The furnace is open in front below the grate.

This opening is closed by a door, E, having a register to regulate the draught.

The upper plate D is of cast-iron, having pot-hole and cover.

The exit-pipe F, when the furnace is used with a cooking-stove, is closed by fitting on it the cap G.

When used independently, this cap is removed, and an elbow and section of ordinary pipe used to conduct off the products of combustion and to create draught.

The cast-iron bottom C has two openings, one within the inner cylinder, and covered by the dumping-plate H, the other between the inner and outer cylin-

ders, extending nearly to the rods I I, and bridged by three cross-bars, h h.

The dumping-plate H is pivoted between the journals i i, turning in the journal-seats e e, and is formed with an under lip on one side of its circumference, and an upper lip on the other side, in such a manner as to permit the plate to turn only in one direction. This dumping-plate is operated by the handle K.

The rods I I connect the upper and lower plates of the furnace, and are fastened securely by the nuts a a, screwed on their lower ends.

The operation of my furnace is as follows:

When used in connection with a cooking-stove, place the cap on the back collar F of the furnace, and removing the cover from one of the pot-holes of the stove, place the furnace thereon. The draught-damper of the stove is now closed, and the back damper opened. The furnace-door is opened, and the cover, being removed from its top, a fire is kindled on the grate b. The products of combustion are carried up over the edge of the inner cylinder B, down the reversible flue Y, formed between the cylinders A and B, into the stove, passing out through the exit-pipe of the stove into the chimney. The ashes that accumulate under the grate, are removed by turning the dumping-plate H, which throws them down into the ash-pit of the stove.

When used independently in the yard or fire-place, the cap G is removed, and an elbow and length of pipe attached to the collar F.

What I claim as my invention, and desire to secure by Letters Patent, is—

The summer-furnace herein described, having dividing-flue Y, dumping-plate H, and cap G, constructed and arranged to operate in connection with an ordinary cooking-stove, or independently, substantially as specified.

In testimony that I claim the above, I have hereunto subscribed my name, in the presence of two witnesses.

Witnesses: J. S. VAN BUREN.
J. J. VAN WIE,
AUSTIN CHILDS.
